CLAIM

The ornamental design for a cosmetic applicator brush-pen, as shown and described.

DESCRIPTION

FIG. 1 is a perspective view of a cosmetic applicator brush-pen showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is an enlarged reference view of brush; and,

FIG. 9 is an enlarged reference view of perspective view.

The broken lines in the drawings are for illustrative purposes only and do not form part of the claimed design.
